Patented June 11, 1918

UNITED STATES PATENT OFFICE.

PIERRE P. GILLES, OF SPRINGFIELD, MASSACHUSETTS.

CARBURETER.

1,269,176.

Specification of Letters Patent. Patented June 11, 1918.

Application filed August 6, 1917. Serial No. 184,736.

to all whom it may concern:

Be it known that I, PIERRE P. GILLES, born in Switzerland of German parentage, now believing myself to be a citizen of the 5 Swiss Confederation, and having formally declared my intentions of becoming a citizen of the United States of America in con- formance with the United States immigra- 10 tion laws, and now residing at Springfield, in the county of Hampden and State of Massachusetts, United States of America, have invented certain new and useful Im- provements in Carbureters, of which the fol- 15 lowing is a specification.

This invention relates to carbureters and more particularly to carbureters of that type which may be automatically supplied with fuel from a low level supply tank. The invention also relates to an improve- 20 ment in carbureters of the type disclosed in my co-pending application Serial No. 170,098, filed May 21, 1917.

An object of the invention is to provide a carbureter having a fuel passage communi- 25 cating at one end with the air intake pipe and adapted for connection at the other end to the main low level supply tank, in such a manner that the suction ordinarily used to draw fuel from the nozzle into the 30 intake pipe is in addition used to draw fuel from the main low level supply tank to the nozzle, together with a supplementary pas- sage from the intake pipe communicating with the fuel passage intermediate its ends 35 and a valve normally closing the supple- mentary passage and automatically operable, when the suction through the fuel nozzle fails to lift sufficient fuel to maintain the fuel supply at its normal level, to open the 40 supplementary passage.

Another object of the invention is to pro- 45 vide in a carbureter, a substantially air tight chamber adapted to be connected to a main low level fuel supply tank, a fuel passage from the chamber to the air intake of the carbureter a suction passage from the intake to the chamber, a float in the latter, and a valve operable by rise and fall of the float to close and open said suction passage, the 50 construction being particularly character- 55 ized in that the chamber is normally kept filled by the suction effective to draw fuel into the intake pipe and at times when this suction becomes insufficient for the purpose, the suction passage is opened to aid in filling the chamber.

Other objects and advantages will appear in the following description and will be particularly pointed out in the appended claims.

The invention, in an embodiment at pres- 60 ent preferred, is disclosed for illustrative purposes in the accompanying drawings, in which:

Figure 1 is a top plan view of a carbureter embodying the invention; 65

Fig. 2 is a sectional elevational view there- 68 of taken on the line 2—2 of Fig. 1;

Fig. 3 is a sectional plan view taken on the line 3—3 of Fig. 2;

Fig. 4 is a fragmentary sectional eleva- 70 tional view taken on the line 4—4 of Fig. 3; and

Figs. 5 and 6 are detail side and end ele- 75 vational views respectively of the valve member shown in Fig. 3.

Referring to these drawings in detail, the carbureter casing comprises a substantially horizontal suction pipe 10, which is open at both ends and adapted for attachment at one end by the flanges shown to the intake 80 manifold of the engine, and a chamber 11, which is preferably integral with pipe 10 and is closed at the top by a suitable cover 12. A fuel inlet pipe 13, removably secured to cover 12 (Fig. 2), is connected at one 85 end through openings in the latter to the upper part of chamber 11. The other end of pipe 13 is adapted for connection directly with a suitable fuel supply tank, not shown, such as a low level supply tank in an auto- 90 mobile, for example.

Referring to Figs. 1 and 3; adjacent the air inlet end of pipe 10 a damper 14 is provided for choking purposes, as will appear, together with a Venturi or choke tube 95 14' which is provided for the usual purposes. Spaced from Venturi 14' is a throttle valve or damper 16 suitably secured to a sleeve 17, which, as shown in Fig. 4, is vertically and rotatably mounted in pipe 10. Fixed to the upper end of sleeve 17 is a suitable lever 18. Pivoted to the latter is a cam 19, a part of which extends into sleeve 17 through a slot therein as shown in Figs. 3 and 4. Threaded into sleeve 17 from the upper end thereof is a rod 20, which may be raised and lowered in the sleeve and has a pointed lower end to engage and move the cam 19 in a manner clearly obvious from Fig. 4. A spring 21 (Fig. 3) connects the cam 19 and throttle 16 and holds the former in engagement with the pointed end of rod 100 105 110 115

20. It will be seen that the inclination of the contour of the cam relatively to the throttle 16 may be varied within limits as desired by turning the rod 20.

5. A horizontal passage 22 formed in the wall of pipe 10 communicates at one end with the interior of the latter and the axes of passage 22 and throttle 16 are arranged to lie in substantially the same vertical 10 plane. At its other end, passage 22 communicates with the upper end of a vertical passage 23 and the lower end of the latter is connected by a horizontal passage 24 with the interior of the chamber 11 near the base thereof as best shown in Fig. 2. The passage 22 is formed with a conical valve seat 25 (Fig. 3) and a valve member 26 slideable in passage 22 has a conical part to engage seat 25 and close the passage. The valve member, as best shown in Figs. 5 and 6, has four flat surfaces 27 arranged at right angles to one another, whereby when said conical part is moved axially out of engagement with seat 25 communication between 25 the suction pipe and that part of passage 22 back of the valve 26 may be had by means of the spaces between surfaces 27 and the peripheral walls of passage 22.

One end of valve 26 extends into pipe 10 30 and is held in engagement with the periphery of cam 19 by a spring 28 disposed within the passage 22. Valve 26 is arranged to be closed when throttle 16 is closed and to be opened automatically when the throttle 35 is opened by the movement of cam 19. The latter causes valve 26 to open proportionately to the opening of pipe 10 by the throttle and the extent of opening may be varied by turning rod 20 as already described.

40. Within chamber 11 is a float 30 and pivotally connected to the upper end thereof are spaced levers 31 which are fulcrumed at 32 to the cover 12. A valve 32', having a stem 33 of substantially square cross section, is arranged to control the communication between the upper part of chamber 11 and a vertical passage 34 in cover 12, the stem 33 being slideable in the passage 34 for guiding the valve, without in itself closing 45 the passage. Valve 32 has two spaced collars 36 thereon between which a cylindrical extension 37 from each lever 31 extends, whereby the rise and fall of float 30 may close and open valve 32' respectively in an 50 obvious manner.

The passage 34 is connected by a passage 38 to the upper end of a vertical passage 39 formed in the wall of pipe 10 and the lower end of passage 39 is connected by a horizontal 55 passage 40 with the interior of pipe 10 and at a point between the throttle 16 and the engine end of pipe 10, whereby the suction produced in the latter is always available in passages 34, 38, 39 and 40 irrespec- 60 tive of the position of the throttle.

The operation of the carbureter will now be described. In originally filling the chamber 11, the choke damper 14 preferably is entirely closed at the start of the filling operation to increase the degree of suction 70 which is effective through the passages 34, 38, 39 and 40 to exhaust the air from chamber 11. Preferably also the throttle 16 is widely opened so that suction may be applied through passages 22, 23 and 24 to aid 75 in filling chamber 11. Obviously, the throttle 16 may be closed or damper 14 may be open to any desired degree at the start of the filling operation but the suction effective for the purposes of exhausting the air from 80 chamber 11 will be of less degree and the filling of the chamber with fuel will be less rapid. With the first described method the air is rapidly drawn out of chamber 11 and the vacuum produced therein causes fuel to 85 flow from the low level supply tank into the chamber. The valve 32' automatically closes after the fuel has reached a certain level in the chamber 11 and as soon as passages 22, 23, and 24 are filled with fuel the 90 throttle 16 may be closed.

In normal operation, the damper 14 is widely opened and the throttle lever 18 is manipulated in the usual manner, to cause varying degrees of opening of throttle 16, 95 and an opening of the latter causes a proportionate opening of valve 26. The suction produced in pipe 10 is thus applied to passages 22, 23 and 24 to draw fuel from chamber 11 into pipe 10 and the withdrawal of 100 fuel from the chamber causes more fuel to flow from the low level delivery tank into the chamber since the latter is air tight. Thus, ordinarily the withdrawal of fuel from chamber 11 by suction through the 105 fuel passages or nozzle is accompanied by a delivery of fuel into the chamber through the operation of the same means. As long as the chamber 11 is filled to a given level with fuel, the valve 32' remains closed as 110 illustrated, but when for any reason the suction through the fuel passages 22, 23 and 24 is insufficient to keep the chamber filled to the desired level, the float 30 falls, opening valve 32' and a supplementary or auxiliary 115 suction is then available to replenish the chamber with fuel.

It will thus be seen that an improved carbureter has been provided, which operates by the suction utilized to deliver fuel into 120 the intake pipe to also supply the fuel nozzle from a low level fuel supply tank, and is characterized by the provision of a supplementary suction passage, which may be automatically called into play when needed, to 125 aid in delivering fuel from the low level tank to the fuel nozzle. As distinguished from vacuum feed systems of the prior art, the vacuum in the fuel chamber is not broken to permit a gravity discharge of fuel 130

- but on the contrary, the discharge of fuel is accomplished wholly by suction, which functions also to supply the fuel chamber from the low level tank, and the supply of fuel to the chamber is not accomplished wholly by the float controlled suction connection but the latter functions only intermittently at times when needed to aid the main suction connection.
- 10 The invention has been described, in an embodiment at present preferred, for illustrative purposes but the scope of the invention is defined by the appended claims rather than by the foregoing description.
- 15 What I claim is—
1. A carbureter, comprising, an air intake passage adapted for connection to suction means, means for maintaining constant fluid communication between said passage and a low level supply tank, all constructed and arranged so that fuel from the latter may be directly supplied to said passage by the suction produced therein, a suction passage connecting the air intake passage and said communication between the tank and intake passage, and a valve normally closing said suction passage and automatically operable at times when needed to open the suction passage, whereby increased suction is available to draw fuel from said tank.
  2. A carbureter, comprising, an air intake passage adapted for connection to suction means, means for maintaining constant fluid communication between said passage and a low level supply tank, a substantially air-tight chamber forming part of said communication, all constructed and arranged so that fuel from the latter may be directly supplied to said passage by the suction produced therein, a suction passage from the intake passage to the chamber, and a valve normally closing said suction passage and automatically operable at times when needed to open the suction passage, whereby increased suction is provided to compensate for the decreased suction available to draw fuel into said chamber.
  3. A carbureter, comprising, an air intake passage adapted for connection to suction means, means for maintaining constant fluid communication between said passage and a low level supply tank, a substantially air-tight chamber forming part of said communication, all constructed and arranged so that fuel from the latter may be directly supplied to said passage by the suction produced therein, a suction passage from the intake passage to the chamber, a float in said chamber, and a valve operable by the rise and fall of the float to close and open said suction passage, respectively, all constructed and arranged so that the chamber is normally kept substantially filled with fuel solely by the suction through said communication and so that supplementary suc-
- tion is automatically provided at times when needed to insure that the chamber is kept filled.
4. A carbureter, comprising, an air intake passage adapted for connection to suction means, a valve to vary the effective opening of said passage, a substantially air tight chamber adapted for direct connection to a low level fuel supply tank, a fuel passage from the chamber to the air intake passage, a valve in the fuel passage to open and close the latter as said intake valve is opened and closed, a second passage from the intake to the chamber, and a valve in the second passage automatically operable when the fuel in the chamber falls to a predetermined level to open the passage, whereby auxiliary suction may be brought into play when needed to aid the suction from first named fuel passage in drawing fuel from the tank into said chamber. 70
5. A carbureter, comprising, an air intake passage adapted for connection to suction means, a valve to vary the effective opening of said passage, a substantially air tight chamber adapted for direct connection to a low level fuel supply tank, a fuel passage from the chamber to the first-named passage, a valve in the fuel passage, means connecting said valves so that an opening or closing of one is accompanied by a proportionate opening and closing of the other, a second passage from the air intake passage to the chamber, and a valve in the second passage automatically operable when the fuel in the chamber falls to a predetermined level to open the passage, whereby auxiliary suction may be brought into play when needed to aid the suction from first named fuel passage in drawing fuel from the tank 85 into said chamber. 90
6. A carbureter, comprising, an air intake passage adapted for connection to suction means, a valve to vary the effective opening of said passage, a substantially air tight chamber adapted for direct connection to a low level fuel supply tank, a fuel passage from the chamber to the first-named passage, a valve in the fuel passage means connecting said valves so that an opening or closing of one is accompanied by a proportionate opening and closing of the other, a second passage from the air intake passage to the chamber, and a valve in the second passage automatically operable when the fuel in the chamber falls to a predetermined level to open the passage, whereby auxiliary suction may be brought into play when needed to aid the suction from first named fuel passage in drawing fuel from the tank 100 into said chamber. 105
7. A vacuum feed carbureter, comprising— 110
- 115
- 120
- 125
- 130

ing, an air intake passage adapted for connection to suction means, an air-tight chamber adapted for connection to a low level supply tank, means for maintaining a constant fluid communication between said tank and chamber and said chamber and passage, a normally closed passage connecting the

chamber and intake passage, and means automatically operable at times when needed to open the last-named passage to provide supplementary suction to draw fuel from the tank to said chamber.

PIERRE P. GILLES.
